ELECTRIC FLATIRON

Carl Anderson, Morningdale, Mass., and Gilbert Adamec, Bronx, N. Y.; said Adamec assignor to said Anderson

Application September 27, 1951, Serial No. 248,505

7 Claims. (Cl. 38—75)

1

This invention relates to electric flat irons.

It is an object of the present invention to provide in an electric flat iron a temperature indicator so that the operator can, at all times, know the exact temperature of the flat iron and a thermostat operable to keep the flat iron within the desired range to which the thermostat has been set for different kinds of materials which are being ironed, and thereby to prevent the damaging of these materials.

It is another object of the invention to provide in an electric flat iron a clock which is automatically wound as the thermostat is set by the operating member so that the operator will at all times have a clock available so that she may time herself on the ironing of different pieces of work which she is doing and also that she will have readily available the time.

It is another object of the invention to provide an electric flat iron where there is provided adequate insulation to prevent the radiation of heat and wherein there is provided in the iron a fan device operated by the thermostat setting mechanism and located between a bottom part and a top part to circulate air therebetween and to further prevent the iron from radiating upwardly great heat.

Other objects of the invention are to provide an electric iron having a cooling means, a clock, a thermostat set and operated by a common operating member, which is of simple construction, inexpensive to manufacture, has a minimum number of parts, light in weight, compact, of pleasing appearance and efficient in operation.

For a better understanding of the invention, reference may be had to the following detailed description taken in connection with the accompanying drawing in which:

Fig. 1 is a perspective view of the electric iron embodying the features of the present invention;

Fig. 2 is an enlarged longitudinal sectional view taken generally on line 2—2 of Fig. 1;

Fig. 3 is an enlarged transverse sectional view taken on line 3—3 of Fig. 2.

Fig. 4 is a fragmentary and perspective view of the clock and the thermostat setting member connected with the clock to wind the same and the wiring diagram including the thermostat and the heating coils.

Fig. 5 is an enlarged slip clutch arrangement in connection with the clock to prevent overwinding and is viewed on line 5—5 of Fig. 4.

Fig. 6 is a fragmentary collective and perspective view of the fan blade and the spring motor parts for operating the same.

2

Fig. 7 is a perspective view of the top of the indicating plate along which the thermostat setting member slides and through which a thermometer can be observed, the thermometer being shown in full and as well shown in connection with the bottom plate part.

Referring now to the figures, 10 represents a bottom part and 11 represents generally the top casing. The bottom part 10 includes a heavy metal piece 12 having a smooth bottom flat iron surface 13, recessed at its top as indicated at 14, electric heating coils 15, lying within the recess 14 and a cover plate 16, recessed on its under side to receive the heating coils 15 and to match with the recess 14 of the heavy bottom plate. This cover plate 16 is made secure to the bottom plate by screws 17. The cover plate is heavily insulated by insulating material 18 to prevent as far as possible, the radiation of heat from the bottom part toward the handle part. Cable wires 19 and 20 run outwardly from the heating coils and one of these cords extends to plug socket 21 on the casing part 11 and at the rear thereof.

Spacing elements 22 and 23 extend through the insulation 18 and engage with the cover plate 16 of the bottom part. These spacing elements are shouldered respectively as indicated at 24 and 25 to support an insulating plate 26 on the underside of the casing 11. The casing is accordingly made secure to the bottom part and held spaced therefrom by the spacing elements 24 and 25 and by screws 27 and 28 respectively passing through transverse bar elements 29 and 30 lying over the top face of the insulating plate 26 and leading respectively through the spacing elements 22 and 23 into threaded engagement with threaded openings in the cover plate 16 of the bottom part 10.

The members 29 and 30 extend transversely and are integral with a top part and enclosing the casing 34 having a top portion 32 and side portions 33 and 34. The side portions and the top portion are cut away at the front to provide a V opening 35 into which is fitted an insulating handle 36 having a front V-shaped portion 37 with an opening 38 therein containing a clock mechanism 39 readable from the front thereof.

This clock mechanism 39 has an attaching plate 41 which is secured by screws 42 to the inner side of the V-shaped portion 37 of the handle 36 to hold the clock mechanism in the opening 38. This plate 41 has a double bent portion 43 which holds a setting mechanism 44, 45 including a small shaft 45 with a gear 46 thereon.

meshing with a setting gear 47 of the clock mechanism 39.

The plate 41 carries a bracket 48 and has a horizontally extending portion 49 and an upright portion 50.

The bracket 48 has on its horizontally extending portion 49 an upstanding bifurcated projection 49' and the vertical portion 50 has a bifurcated projection 50'. These bifurcated projections support a flexible cable shaft 51 which at its forward end has a coupling member 52 that clutches a square winding shaft 53 of the clock mechanism 39. The rearward end of the flexible cable 51 has overloading clutch device 54 with relatively adjustable parts 55 and 56. These parts have ball elements 57 normally held in recesses 58 of the part 55 by biasing springs 59 in the part 56. The part 56 has a gear 60 secured thereto which lies rearwardly of the projection 49'. The part 56 is journaled in the projection 49' and the clutch parts 55 and 56 will normally turn the cable 51 so as to wind the shaft 53 of the clock mechanism. Should the clock mechanism be already tightly wound, there will be slippage of part 56 over the part 55. Journaled on the member 56 is a shaft 61 to which gear 62 is fixed. This gear 62 meshes with the gear 60 and with a rack 63 and with teeth 63' on the underside thereof.

This rack 63 is slideable through the handle part 11 and under the top portion 32 of the cover member 31. The top portion 32 has elongated slot 64 upwardly through which extends an operating handle 65 on the rear end of the rack 63. On the upper end of the handle 65 is a button 66. Indicating arms 67 and 68 extend outwardly from the button and from the operating arm 65 and are slideable over a plate 69 having temperature indications 69 and 70 on the respective opposite sides thereof. The indications 69 will indicate the location to which the button 66 is moved for the different materials being ironed. The indicating point 67' will be moved to the indications 70 for temperature readings for a thermometer 71 having a bulb 72 disposed in the bottom part 10. The indications are on a plate 73 which is connected by screws 74 to the top portion 32 and which itself has an elongated opening 75 registering with the opening 64 in the top portion 32 and an elongated opening 76 along which a bent portion of a thermometer tube 77 extends. Fig. 7. The thermometer bulb 72 is held in the bottom part 12 by a threaded member 77 engaging with cover member 16 of the bottom part.

It will be apparent that as the rack 63 is adjusted each time, the clock 39 will be wound and if it is already tightly wound, then the clutch 54 will permit slippage so that further winding will not be effected.

In order to be certain that heat is not radiated from the bottom part 13 toward the handle and in addition to the insulating members 18 and 26, there is provided in the space between the insulating members a fan blade 78. This fan blade has a shaft 79 and coupling plate 80 which are secured to a gear plate 81. The shaft 79 is journaled in a cup shaped bracket member 82 which is secured to the underside of bracket 48. The shaft 79 extends downwardly through an opening 83 in the insulating plate 23. The blade 78 swings free on the lower end of the shaft 79 and as the shaft 79 is stepped about by the plate 81, the fan blade 78 is kept in rotation and made to spin. The plate 81 moves in a step to step fashion by escapement device 84, resisting the con-

tinued turning power of coil spring 85 anchored at 86 to the gear plate 81. The inner end of the spring 85 is anchored at 87 to a shaft 88 and has a ratchet wheel 89 thereon which cooperates with a pawl 91 that prevents the unwinding of the spring 85 as it is wound. A one-way clutch arrangement 92 is provided between shaft 88 and a shaft 93 which has a gear 94 thereon that coacts with gear teeth 63" of the rack 63, and accordingly as the rack 63 is adjusted each time the iron is used, the spring 85 for operating the fan blade 78, wound. The one-way clutch 92 prevents overwinding of the spring 85.

Accordingly, air is taken into the space between the insulating plates 18 and 25 from the exterior of the iron and will be discharged outwardly through other openings whereby to keep a circulation of air between the insulating plate and to remove the heated air. This provides an air cooling means to prevent the electric iron from becoming overheated and difficult to handle. There will be through this means little radiation toward the handle which is grasped by the user. Holes 95 through which air can pass are provided in the side portions 33 and 34.

The rack 63 has a laterally extending fork member 96 secured thereto which receives an upstanding rod 97 of a thermostat arm 98 extending from thermostat 99. This thermostat has terminals 100 and 101. The wire 20 connects with the terminal 100 and a wire 102 connects with a terminal 101 and extends to plug receptacle 21 on the rear end of the handle part 11 to which the iron plug is releasably connected. Accordingly, the same rack 63 serves several functions. It serves to wind the clock, wind the air fan mechanism, adjust the thermostat and to indicate the position of adjustment of the thermostat. It should be further apparent that there has been provided an air cooling means whereby heated air in the space between the insulating members is removed so that there will be little heating of the upper insulating member 26.

While various changes may be made in the detail construction, it shall be understood that such changes shall be within the spirit and scope of the appended claims.

What is claimed is:

1. An electric iron comprising a bottom having heating elements therein, a top casing having top and side portions, spacing elements securing said bottom and said casing and providing air spaces between the bottom and the casing, air fan means lying in the space between the bottom and the casing, operating mechanism carried by said iron for operating said air fan means, and settable thermostat means connected with the heating elements of the bottom retained by the top casing, said operating mechanism for the air fan including a spring element, and a common operating element winding the spring element and for adjusting the thermostat means.

2. An electric iron comprising a bottom having heating elements therein, a top casing having top and side portions, spacing elements securing said bottom and said casing and providing air spaces between the bottom and the casing, air fan means lying in the space between the bottom and the casing, operating mechanism carried by said iron for operating said air fan means, and a clock mechanism mounted on the casing, shaft means for winding the clock mechanism, said air fan operating means including a spring element and

a common operating member adjustable to wind the air fan operating mechanism and the clock mechanism mounted on the casing part.

3. An electric iron comprising a bottom and a top casing connected to the bottom, said bottom having heating elements, thermostat means connected to the heating elements and carried by the casing, said thermostat means having a settable arm, a clock mechanism mounted on the casing, shaft means for winding the clock mechanism and a common operating member connected to the clock mechanism and to the settable arm of the thermostat means whereby upon the thermostat means being set each time the clock mechanism will be wound.

4. An electric iron comprising a bottom and a top casing connected to the bottom, said bottom having heating elements, thermostat means connected to the heating elements and carried by the casing, said thermostat means having a settable arm, a clock mechanism mounted on the casing and a common operating member connected to the clock mechanism and to the settable arm of the thermostat means whereby upon the thermostat means being set each time the clock mechanism will be wound, and a flexible shaft provided with the clock mechanism and including clutch means whereby upon the clutch mechanism being fully wound, the operating member can be disengaged therefrom within the flexible shaft means.

5. An electric iron, as defined in claim 2, and thermostat means connected to the heating elements and carried within the casing, said thermostat means having a settable arm and said common member for the air fan operating

mechanism and the clock mechanism connected to the settable arm of the thermostat means whereby upon each time the thermostat means is set, the clock mechanism and the air fan mechanism will be wound.

5 6. An electric iron, as defined in claim 3, and an air fan means disposed between the bottom and the top casing and a winding spring mechanism for operating the same, said winding spring means connected with the common operating member for the thermostat and the clock mechanism whereby to be simultaneously operated thereby.

10 7. An electric iron, as defined in claim 6, and 15 said operating member having two rows of rack teeth and said shaft means for winding the clock mechanism having gear means operable upon one row of rack teeth and said winding spring means for the air fan means having gear connection 20 with the other row of rack teeth to be driven by the same.

CARL ANDERSON.
